UNITED STATES PATENT OFFICE.

WILLIAM H. REYNOLDS, OF DE SOTO, MISSOURI.

OIL-CAN.

1,300,019.

Specification of Letters Patent.

Patented Apr. 8, 1919.

Application filed September 18, 1918. Serial No. 254,631.

To all whom it may concern:

Be it known that I, WILLIAM H. REYNOLDS, a citizen of the United States, residing at De Soto, in the county of Jefferson and State of Missouri, have invented new and useful Improvements in Oil-Cans, of which the following is a specification.

This invention has reference to improvements in dispensing cans, particularly to oil cans in which the oil is ejected by compressing the flexible bottom thereof, and the primary object of the invention is to produce a simple means for returning the bottom to its initial position after the same has been forced inwardly in dispensing the oil through the spout of the can.

An object of the invention is to produce a means for this purpose in the nature of a spring ring arranged in the can adjacent to the bottom thereof and held therein by contact with an inturned bead formed on the can, said ring being centrally provided with depending spring fingers that contact with the inner face of the bottom of the can and return the same to its normal position after pressure has been exerted in an inward direction upon the outer surface thereof.

A further object of the invention is to produce a device of this character which may be attached in an ordinary can or which may be formed with the can in the process of manufacture thereof.

It is a still further object of the invention to produce a device of this character which shall be of an extremely simple construction, cheap to manufacture and thoroughly efficient in the purpose for which it is devised.

Other objects and advantages will present themselves as the nature of the invention is better understood, reference being had to the accompanying drawing, in which:

Figure 1 is an approximately central vertical longitudinal sectional view through the can provided with the improvement;

Fig. 2 is a horizontal sectional view approximately on the line 2—2 of Fig. 1; and

Fig. 3 is a perspective view of the improvement.

In the drawings I have illustrated the improvement in connection with an ordinary oil can from which a lubricant is dispensed by compressing the flexible bottom thereof.

The can is indicated by the numeral 5 having at its mouth a threaded neck 6 in which is screwed the wider end of the outlet spout 7.

The flexible bottom 8 for the can has a substantially U-shaped depressed portion at the periphery thereof forming a continuous channel that is designed to receive the edge of the can body, the sides of the portions providing the channel being compressed against the edge of the can body, and if necessary soldered thereto. The bottom is in this manner removably connected to the body of the can but is designed to remain a permanent element therewith after the improvement is arranged in the bottom of the can.

The body of the can 5, a suitable distance inward of the bottom thereof is formed with an inturned annular depression providing, upon the inner surface of the said body a continuous bead 9. The can is preferably but not necessarily round in cross section and the lower wall of the bead is designed to contact with the edge of a flat spring ring 10. The ring 10, a suitable distance from the edge thereof is formed with a continuous circumferential depression providing 80 the under face thereof with a rib 11 that serves as a reinforcing element for the body of the ring.

The ring 10, upon its inner periphery is integrally formed with eight angularly disposed inwardly extending spring fingers 12. These fingers are designed to be bent at an angle, in the same direction, from the ring and to contact with the inner face of the bottom of the can. The ring is provided with an annular depression forming the same with a reinforcing rib 11.

The compressible bottom 8 is forced inward of the can in the usual manner, when the oil is to be ejected through the spout 7. In the ordinary construction of such cans continual pressure against the bottom interferes with the resiliency thereof, so that in a comparatively short period of use the cans become useless. With my improvement the spring fingers 12 constantly contacting with the bottom 8 retain the same in its ordinary position, and also return the said bottom to its initial position after pressure thereon has been released. The spring fingers 12 also serve to hold the edge of the plate 10 in contact with the bead 9, so that no additional means is necessitated in properly holding the plate positioned in the can.

Having thus described the invention, what is claimed as new, is:

1. In combination with a can having a

compressible bottom, of a flat ring seated in the can adjacent to said bottom, means carried by the can and engaged by the ring for holding the ring against movement in an upward direction, and spring fingers formed on the inner edge of the ring and extending inward at an angle therefrom contacting with the bottom of the can.

2. In combination with a can having a continuous inturned bead adjacent to the

bottom thereof, of a flat ring in said can contacting with said bead, said ring having a continuous reinforcing rib, and radially disposed angularly arranged spring fingers on the inner edge of said ring contacting with the bottom holding the latter in one position and retaining the ring in rib contacting position.

In testimony whereof I affix my signature.

WILLIAM H. REYNOLDS.
